UNITED STATES PATENT OFFICE.

HERBERT GREGSON, OF WEEHAWKEN, NEW JERSEY.

TOBACCO-PIPE.

1,395,817.

Specification of Letters Patent. Patented Nov. 1, 1921.

Application filed November 22, 1919. Serial No. 340,055.

To all whom it may concern:

Be it known that I, HERBERT GREGSON, a citizen of the United States, and a resident of Weehawken, in the county of Hudson and State of New Jersey, have invented a new and Improved Tobacco-Pipe, of which the following is a full, clear, and exact description.

The object of the invention is to provide a new and improved tobacco pipe arranged to prevent burning out of the base of the bowl and thus insuring long life of the pipe.

Another object is to provide a chamber for the reception of the nicotin to prevent the latter from passing into the pipe stem and to the mouth of the smoker.

Another object is to provide an even draft in the base of the bowl and thus insure a proper uniform burning of the tobacco and consumption of practically all the tobacco with which the bowl is filled by the user.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a longitudinal sectional elevation of the improved tobacco pipe with the stem and portion of the stummel shown in elevation;

Fig. 2 is a plan view of the bowl and a portion of the stummel; and

Fig. 3 is a longitudinal sectional elevation of a modified form of the tobacco pipe, with the stem and part of the stummel shown in elevation.

The tobacco pipe illustrated in Figs. 1 and 2 comprises essentially a bowl 10 having an integral stummel 11 connected with the stem 12 terminating in the mouthpiece 13. In the base of the bowl 10 is arranged a centrally disposed protuberant member 15 having a rounded off top and forming with the wall of the base portion of the bowl 10 an annular draft chamber 16 connected with the bore 17 of the stummel 11. The bore 17 enters the annular chamber 16 a distance above the bottom of the bowl and a distance below the top of the protuberant member 15. By the arrangement described the upper

portion of the protuberant member forms a support for the tobacco with which the bowl 10 is filled by the user so that the tobacco does not free the annular chamber 16 but leaves the latter practically unobstructed. 60 The bottom of the charge of tobacco usually extends a short distance below the top of the protuberant member 15 but does not reach to the bore 17, and hence when the pipe is in use a uniform draft is had in the 65 chamber 16 to insure uniform burning of the tobacco in the bowl 10. It will further be noticed that by the arrangement described the base portion of the bowl 10 is not subjected to the burning action of the tobacco 70 and hence the base of the bowl is not liable to be burned out and consequently long life of the pipe is insured. It will further be noticed that the bottom portion of the annular chamber 16 on account of being below 75 the bore 17 allows the nicotin to accumulate therein and hence nicotin is not liable to pass through the bore 17 to the mouth of the smoker. A further advantage derived from the construction of the bowl as set 80 forth is that the tobacco can practically be all burned and hence no tobacco is wasted.

In the modified form shown in Fig. 3, the bowl 20 is provided at the bottom with a threaded reduced portion 21 which screws 85 into the base 22 from which extends the stummel 23 connected with the stem 24. The bowl 20 is provided in its base portion with a centrally arranged protuberant member 25, similar to the protuberant member 15 above 90 referred to, and forming an annular chamber 26 with the wall of the bowl 20. From the bottom of this chamber 26 leads a bore 27 to the bottom of the reduced portion 21 and this bore 27 connects with the bore 28 95 formed in the base 22 and stummel 23. The functions of the protuberant member 25 are practically the same as above described in reference to the protuberant member 15 and the bowl 10, and hence further description 100 of the same is not deemed necessary.

Having thus described my invention, I claim as new and desire to secure by Letters Patent:—

1. In a tobacco pipe, a bowl provided at 105 its base with a centrally disposed protuberant solid member forming with the wall of the bowl an annular draft chamber from which leads a bore connected with the pipe stem, the said bore opening into one side 110

of the said annular draft chamber above the bottom thereof and a distance below the top of the said protuberant member.

2. In a tobacco pipe, a bowl provided with 5 a stummel and a stem connected with the stummel and provided with a mouthpiece, the said bowl being provided in its base with a centrally disposed protuberant member integral with the base and rising there-

from, the said protuberant member forming 10 with the wall of the base portion of the bowl an annular draft chamber, the said protuberant member being solid and rounded off at the top, the said stummel having a bore 15 leading into one side of said draft chamber at a point intermediate the top and bottom of the said draft chamber.

HERBERT GREGSON.
